SIGNALING DEVICE

Application filed December 1, 1930. Serial No. 499,334.

This invention relates to certain new and useful improvements in signaling devices.

The main object of the invention is to produce a signaling device of efficient, economical and durable construction and which shall have a pleasing appearance while adapted for mounting, with small consumption of space.

Further detailed objects reside in a particular disposition of the elements, their form and relation and the method of relative securement, all as will more fully appear from the following description taken in connection with the accompanying drawings in which:

Figure 1 is a front elevation of the signaling device.

Figure 2 is a section on line 2—2, Figure 1.

Figure 3 is a perspective view of the screen.

Figure 4 is an enlarged view of a broken-away section of the screen.

Figure 5 is a section on line 5—5, Figure 1.

Generally speaking, the signaling device, as illustrated, is of the diaphragm type, and as the operating mechanism therefor forms no portion of this invention, the actual means for vibrating the diaphragm has not been illustrated as any usual well-known mechanism may be provided; the same, however, is preferably of the magnetically actuated type.

The structure, as shown, comprises a diaphragm casing 1 comprising a rear diaphragm case section 2 and a front diaphragm case section or ring 3, between which sections the edge or periphery of a substantially circular diaphragm 4 is clamped, the two sections being secured together in any suitable manner as by bolts 5, any number of which may be provided.

In the particular structure illustrated, the diaphragm 4 carries a supplemental free edge diaphragm or resonator 6, all in a manner well known in this art.

It has been customary in the use of structures similar to the one so far described, to provide an elongated projector or megaphone for directing and amplifying the sound waves. The present structure departs from that form of device in the provision of a concavo-convex cover or cap 7 provided at its edge with an annular flange 8 fitting around and outside of the edge of the diaphragm case

1, and this cover or cap is secured in place as by bolts 9 extending through depressed portions 10 of the cap and through the edge of the diaphragm case. This cover or cap is provided with a plurality of openings adapted to permit the passage of sound waves as generated by vibration of the diaphragm 4 and resonator 6.

In view of the fact that in the use of a device of this character, dust, dirt and foreign matter tend to pass through the openings in the cap or cover and collect on the operating parts of the mechanism tending to reduce its efficiency, we have provided a wire mesh screen 30 of unique form and supported in a novel manner and which adds to the design and appearance of the signaling device and in which the screen is maintained rigidly and permanently in a predetermined position.

The form of this screen is perhaps best illustrated in Figure 3, and comprises a central substantially circular section 11 formed with radial projecting flanges 12 spaced apart by cutaway portions or recesses 13 in the periphery of the screen. The central portion of the screen is preferably concavo-convex conforming substantially to the general contour of the cover or cap 7 and the projecting portions or flanges 12 are deflected or offset rearwardly so as to lie at an angle to the general contour of the screen.

For the purpose of securing the screen to the cover, the screen may be provided with a central opening 14 fitted over a stud 15 secured to cover 7 and is held in position on the stud as by means of nut 16.

When the cover 7 carrying the screen 30 is fitted over the edge of the diaphragm case 1, the recesses 13 register with depressed portions 10 in the cover, or with bolts 5 through the diaphragm casing, and the deflected flange portions 12 have their outer edges brought into contact with the diaphragm clamping ring 3, and when the bolts 9 are positioned and the parts are drawn together by threading nuts 31 on bolts 9, the deflected flange portions 12 are redirected and tensioned toward a position where they conform with the general contour of the

screen, and this redeflecting of the portions 12, maintains the screen at all times, under tension between the cover 7 and the ring 3, and by this means of utilizing a single stud 5 15 and nut 16, the screen is maintained tightly in desired position covering the openings 17 and 18 in the cap or cover 7 to prevent the entry of foreign matter to the space within the cover.

10 For the purpose of adding to the pleasing ornamental appearance of the horn, the screen, as best illustrated in Figure 4, has sections 20 and 21 of different colors. For illustration, as here shown, the concentric 15 central openings 18 disclose a portion 20 of the screen which is colored red, and the outer concentrically arranged opening 17 disclose portions 21 of the screen that are colored blue so that in addition to its mechanical 20 function, the screen, as here positioned, is made to constitute an ornamental feature of the device.

The effectiveness of this coloring is increased by also coloring the diaphragm 4 and 25 the resonator 6 with colors conforming with the color of that portion of the screen which they are directly behind or with which portions of their surfaces register.

The resultant structure is of ornamental, 30 pleasing appearance, efficient in operation and relatively permanent in construction, and although we have shown and described a specific construction of signaling device and the particular arrangement and relation of the 35 parts thereof, we do not desire to restrict ourselves to any particular form or construction of operating mechanism or to any preferred details as disclosed, except as the same may be definitely included in the claims hereto 40 appended.

We claim:

1. A signaling device comprising a diaphragm case, a vibratory diaphragm carried thereby, a front cover for said case and having 45 openings therethrough, means for securing the front cover to the diaphragm case and a screen interposed between the diaphragm and the case and covering the openings in the latter and said screen having an edge portion 50 deflected when the cover is secured in position with respect to the case, to thereby maintain such edge portion under tension and hold the screen in position.

2. A signaling device comprising a diaphragm case, a vibratory diaphragm carried thereby, a front cover for said case and having openings therethrough, means for securing the front cover to the diaphragm case and a screen interposed between the diaphragm 60 and the case and covering the openings in the latter and said screen having flanges at its edge deflected when the cover is secured in position with respect to the diaphragm case to maintain the flanges under tension and hold the 65 screen in position.

3. A signaling device comprising a diaphragm case including a rear case section and a front case section, a diaphragm having its edge clamped between said sections, a convex cover having openings therethrough 70 and a marginal flange telescoped with the diaphragm case, a screen between the diaphragm and the cover and having flanged portions tensioned to maintain the screen in position when the cover is 75 secured to the diaphragm case, and means for securing the cover to the diaphragm case.

4. In a signaling device, a diaphragm case, a diaphragm carried thereby, a convex cover having openings therethrough, a screen between the diaphragm case and the cover and having edge flanges normally bent so as to lie 80 at an angle to the normal contour of the screen, means for securing the cover to the diaphragm case, such securement of the parts 85 acting to deflect the bent edges of the screen and place them under tension to maintain the screen in position.

5. A signaling device comprising a diaphragm case, a vibratory diaphragm carried 90 thereby, a front cover for said case and having openings therethrough, means for securing the front cover to the diaphragm case and a screen interposed between the diaphragm 95 and the case and covering the openings in the latter, means for maintaining the screen in position, and additional means for securing the screen to the cover.

6. A signaling device comprising a diaphragm case, a vibratory diaphragm carried 100 thereby, a front cover for said case and having openings therethrough, means for securing the front cover to the diaphragm case and a screen interposed between the diaphragm 105 and the case and covering the openings in the latter and said screen having an edge portion deflected when the cover is secured in position with respect to the case, to thereby maintain such edge portion under tension and hold the screen in position, and additional means for securing the screen to the cover.

7. A signaling device comprising a diaphragm case, a vibratory diaphragm carried 110 thereby, a front cover for said case and having openings therethrough, means for securing the front cover to the diaphragm case and a screen interposed between the diaphragm and the case and covering the openings in the latter 115 and said screen having flanges at its edge deflected when the cover is secured in position with respect to the diaphragm case to maintain the flanges under tension and hold the screen in position, and additional means for securing the screen to the cover.

8. A signaling device comprising a diaphragm case including a rear case section and a front case section, a diaphragm having its edge clamped between said sections, a convex cover having openings therethrough and a 120

marginal flange telescoped with the diaphragm case, a screen between the diaphragm and the cover and having flanged portions tensioned to maintain the screen in position 5 when the cover is secured to the diaphragm case, and means for securing the cover to the diaphragm case, and additional means for securing the screen to the cover.

9. In a signaling device, a diaphragm case, 10 a diaphragm carried thereby, a convex cover having openings therethrough, a screen between the diaphragm case and the cover and having edge flanges normally bent so as to lie at an angle to the normal contour of the 15 screen, means for securing the cover to the diaphragm case, such securing of the parts acting to deflect the bent edges of the screen and place them under tension to maintain the screen in position, and additional means 20 for securing the screen to the cover.

10. A signaling device comprising a diaphragm case, a vibratory diaphragm carried thereby, a front cover for said case and having openings therethrough, means for securing 25 the front cover to the diaphragm case and a screen interposed between the diaphragm and the case and covering the openings in the latter, and means for maintaining the screen in position, said screen having sections 30 differently colored and registering with various openings in the cover.

11. A signaling device comprising a diaphragm case, a vibratory diaphragm carried thereby, a front cover for said case and having 35 openings therethrough, means for securing the front cover to the diaphragm case and a screen interposed between the diaphragm and the case and covering the openings in the latter and said screen having an edge portion 40 deflected when the cover is secured in position with respect to the case, to thereby maintain such edge portion under tension and hold the screen in position, said screen having sections differently colored and registering with various 45 openings in the cover.

12. A signaling device comprising a diaphragm case, a vibratory diaphragm carried thereby, a front cover for said case and having openings therethrough, means for securing 50 the front cover to the diaphragm case and a screen interposed between the diaphragm and the case and covering the openings in the latter and said screen having flanges at its edge deflected when the cover is 55 secured in position with respect to the diaphragm case to maintain the flanges under tension and hold the screen in position, said screen having sections differently colored and registering with various openings in the 60 cover.

13. A signaling device comprising a diaphragm case including a rear case section and a front case section, a diaphragm having its edge clamped between said sections, a convex 65 cover having openings therethrough and a

marginal flange telescoped with the diaphragm case, a screen between the diaphragm and the cover and having flanged portions tensioned to maintain the screen in position when the cover is secured to the diaphragm case, and means for securing the cover to the diaphragm case. 70

14. In a signaling device, a diaphragm case, a diaphragm carried thereby, a convex cover having openings therethrough, a screen between the diaphragm case and the cover and having edge flanges normally bent so as to lie at an angle to the normal contour of the screen, means for securing the cover to the diaphragm case, such securing of the parts 75 acting to deflect the bent edges of the screen and place them under tension to maintain the screen in position, said screen having sections differently colored and registering with various openings in the cover. 80

15. A signaling device comprising a diaphragm case, a vibratory diaphragm carried thereby, a front cover for said case and having openings therethrough, means for securing the front cover to the diaphragm case 90 and a screen interposed between the diaphragm and the case and covering the openings in the latter, means for maintaining the screen in position, additional means for securing the screen to the cover, said screen 95 having sections differently colored and registering with various openings in the cover.

In witness whereof we have hereunto set our hands this 19th day of November 1930.
